UNITED STATES PATENT OFFICE.

LORENZO PREZIOSI, OF BROOKLYN, NEW YORK.

CABINET.

Application filed March 3, 1921. Serial No. 449,380.

To all whom it may concern:

Be it known that I, LORENZO PREZIOSI, a subject of the King of Italy, and a resident of the borough of Brooklyn, county of 5 Kings, city and State of New York, have invented certain new and useful Improvements in Cabinets, of which the following is a specification.

My improvements relate to cabinets for 10 the accommodation and storage, temporarily or otherwise, of various articles, such for instance as piano music rolls, phonographic records, files, papers, documents, etc.; in fact, for the convenient and accessible safe- 15 keeping of portable objects and appurte- nances generally, the main object being to attain a simple, compact, combination and arrangement of parts by means of which doors are dispensed with while ample pro- 20 vision is made for the closure of the cabinet and the protection of its contents,—the in- vention consisting essentially in the specific construction described and claimed, and a 25 distinctive feature being the twin container compartments pivotally mounted on and in a common frame work, and simultaneously openable and closable with relation to each other, substantially in the manner and for the purpose set forth.

30 In the accompanying drawings,

Fig. 1, is a front view of my improved cabinet, closed;

Fig. 2, is a front view of said cabinet, opened up;

35 Fig. 3, is a horizontal section taken upon plane of line 3—3, Fig. 1;

Fig. 4, is a horizontal section taken upon plane of line 4—4, Fig. 2;

Fig. 5, is a view of the under side of the 40 top plate or member of the frame work;

Fig. 6, is a section thereof taken upon plane of line 6—6, Fig. 5;

Fig. 7, is a plan or top view of the bottom plate or member of the frame;

45 Fig. 8, is a section taken upon plane of line 8—8, Fig. 7;

Fig. 9, is a sectional detail showing one of the central guide trunnions and its en- gaging channel;

50 Fig. 10, is a sectional detail illustrating the means of pivotal connection between the twin compartments, and one of the guide trunnions in engagement with one of the controlling channels;

55 Fig. 11, is a diagram illustrative of the

positions assumed by the twin compartments during the opening and closing thereof.

Fig. 12, is a top view of one of the rotative compartments, showing one of the central pivotal trunnion studs. 60

The supporting frame work of my duplex cabinet consists of a bottom member f , hereafter called for convenience the bottom plate, the top member f' , hereinafter designated as the top plate, and the four corner 65 standards or uprights f^1 , f^2 ,—the spaces between said standards f^1 , f^2 , being open and free to permit of the requisite rotative manipulation of the twin compartments C , C , which are mounted between said upper and 70 lower plates f' , f .

The compartments C , C , are duplicates, in that each consists of a back c , and two side members c' , c'' , secured rigidly to top members c^2 , and bottom members c^3 ,—the 75 other or frontal portion of each vertical elongate rectangular box thus constituted being open, and the requisite number of spaced-apart shelves c^4 , c^5 , being supported upon and between said back and side boards 80 c , c' , c'' , in any suitable manner known to the art. When the compartments are in closed relationship, as in Figs. 1 and 3, the open sides of the compartments are in coincidence, as shown more particularly in Fig. 85 3; whereas, when the cabinet, considered in a unitary sense, is opened up to render the shelf spaces accessible, these open sides of the compartments C , C , occupy a common plane at the front of the cabinet frame, as 90 shown more particularly in Fig. 4, of the drawings.

In order to attain these results in a facile manner I mount my twin compartments C , C , on roller bearings either countersunk in 95 the under sides of the bottom members c^3 , of the compartments C , themselves, or preferably, as shown in the accompanying drawings, on roller bearings b , b , countersunk in the upper sides of the base member or plate 100 f , of the frame work,—the rotative movements of said compartments being controlled by means of trunnion studs t , t' , engaging with the sides of guide slots g , g' , as hereinafter more fully set forth, and the ad- 105 jacent front edges of the side walls c'' , c'' , of the compartments C , C , being pivotally connected so as to cause the two said twin compartments to move simultaneously and in unison in opposite directions of rotation. 110

As in the case of the ball bearing supports b, b , the arrangement of trunnion studs t, t' , and guide slots g, g' , may be alternative in that the trunnion studs t, t' , might obviously be positioned on the top and bottom plates f, f' , and engage with guide slots in the top and bottom end members of the compartments C, C , with like results, instead of the inverse arrangement of said parts 10 shown in the drawings, although the latter arrangement is preferable, and consists in providing the top and bottom plates f', f , of the frame with guide channel inserts g, g' , for the reception of trunnion studs t, t' , 15 on the end members c^2, c^3 , of the twin compartments C, C . Thus, as will be seen by reference more particularly to Figs. 5 and 7, of the drawings, said end members c^2, c^3 , are provided with guide channels g, g' , extending 20 medially and substantially from front to rear thereof, for the reception of the trunnion studs t, t' , which in this case are coincident with the pintles h', h' , of the hinges h, h , by means of which the aforesaid adjacent 25 front edges of the side walls c'', c'' , are pivotally connected, this feature of construction being shown in detail particularly in Fig. 10. The function of these hinge trunnion studs t, t' , is to maintain the juxtaposition 30 and alignment of the said front edges of the compartment side walls c'', c'' , under all conditions, and to act in conjunction with the pivotal trunnions t' , in controlling the rotative movements of the said twin compartments. To this end the pivotal trunnions t' , are positioned centrally on the top 35 and bottom members c^2, c^3 , of the compartments C, C , as shown in Fig. 12, and engage with transverse guide channels g', g' , 40 in the top and bottom plates f', f , of the frame, and are positioned medially as related to the back and front thereof, as shown in Figs. 5 and 7. The function of the pivotal trunnions t' , is to insure the axial rotation 45 of the twin compartments C, C , and the transverse guide channels g', g' , allow them to do this while compensating for the lateral side thrust, in opposite directions, of the compartments incidental to their pivotal connection with each other as aforesaid. 50

It is of course to be understood in this connection that the sets of guide grooves g, g' , and the trunnion studs t, t' , are duplicated at top and bottom of the cabinet for each container C .

In Fig. 11, of the drawings, I indicate diagrammatically the evolutions involved in the opening or closing of the twin compart-

ments C, C , the solid lines $x-x$, representing either the open or closed position thereof; the lines $y-y$, the intermediate positions of the compartments; and the lines $z-z$, the prescribed arcs of circles traversed by the free corners of the compartments during rotative transition in either direction. It is to be noted in this connection that the lines $z-z$, of the free corner movement of the compartments C, C , are entirely within and clear the corner posts or standards f^2, f^2 , of the frame work; and that the twin compartments are rotative to the extent of a quarter turn in either direction, their pivotal connection preventing more than that extent of movement, and maintaining their alignment and co-relation. 60 65 70 75

By means of my twin compartments thus arranged, combined and connected, I obviate the necessity for the use of doors, while attaining a closable cabinet with a maximum of capacity in a minimum of space. Furthermore my duplex cabinet is simple both in construction and operation, and may be manipulated with facility. 80

What I claim as my invention and desire to secure by Letters Patent is, 85

1. A doorless closable cabinet of the character designated, comprising a supporting frame, pivotally connected rotative twin compartments mounted therein, each with an open side and said open sides coincident 90 when the compartments are in closed relationship, and guide channels and engaging trunnion studs arranged to control the rotative movements of said twin compartments.

2. A doorless closable cabinet of the character designated, comprising a supporting frame, rotative twin compartments mounted therein and pivotally connected to each other at adjacent edges only, each with an open side and said open sides coincident when 100 the compartments are in closed relationship, and guide channels and engaging trunnion studs arranged to control the rotative movements of said twin compartments. 95

3. A doorless closable cabinet of the character designated, comprising a supporting frame having guide-channelled top and bottom members, and twin compartments mounted therebetween, said twin compartments being pivotally connected at adjacent 110 edges and being fulcrum connected with said guide channels in the top and bottom members of the frame. 105

Dated Feb. 28th, 1921. Brooklyn, N. Y.
